UNITED STATES PATENT OFFICE

ALFRED LAURAIN, OF PARIS, FRANCE

BRACE FOR PERSONAL WEAR

Application filed February 18, 1931, Serial No. 516,720, and in France February 20, 1930.

The present invention relates to braces or trouser suspenders and has more particular reference to the type of braces for personal wear comprising a pair of shoulder straps 5 and one or more back straps interconnected to one another by, or engaging through, a separate back pad, said straps being formed of elastic or non-elastic webbing and having means at their free ends for removably en- 10 gaging associated means on the trousers to be suspended, for example tabs formed with button-holes for engaging buttons sewn to said trousers.

The primary and general object of the invention is to provide braces of the aforesaid 15 type with means for preventing the wearer's shirt or similar garment from puckering or wrinkling up into the space comprised between his nape and the back pad interconnect- 20 ing the straps of his braces, such as often takes place under repeated stresses as those which incidentally occur when walking, running, jumping, riding, bowing or effecting similar movements in daily life, when prac- 25 ticing sports or games or in similar circumstances.

A more specific object of the invention is to provide the back strap and/or the back pad of the braces with an inner surface of 30 rough or roughened, adhesive or gripping nature so as to create a friction or adherrence between said surface and the underlying shirt or similar garment and thus to check any tendency of the latter to pucker or wrinkle up.

Still a more specific object of the invention 35 is to provide the back strap and/or the back pad of the braces with an adhesive or gripping inner surface constituted by a plurality of tapes, fillets, plaits or more generally cord-like protuberances advantageously formed of several parallel strands of rubber or like gripping substance stitched or bound by weaving at short intervals to the supporting 40 foundation, the stitches being conveniently staggered from one strand to the next ones for giving the cord-like protuberances a chain-like structure for still enhancing the frictional effect.

Still a more specific object of the invention

is to provide the back strap and/or the back pad or pads of the braces with frictional or gripping cord-like protuberances on their inner surface in contact with the underlying garment, each of said protuberances having a 55 chain-like structure and being provided on either sides with quincuncial textile borders adapted to protect it from chafing and other causes of premature wear, said borders being chosen, if required, for aesthetically matching with the said protuberances and other parts of the braces.

With these and such other objects in view as will incidentally appear hereafter, the invention comprises the features that will now 65 be described with reference to the accompanying drawings which exemplify same in several embodiments and wherein:

Figure 1 is a fragmentary view showing, viewed from the inner surface thereof, a 70 brace back pad interconnecting two shoulder straps with a back strap and fitted with a plurality of friction or adhesive tapes or cords of chain-like structure.

Figure 2 is a similar view to Figure 1 showing a brace back pad of slightly different 75 form.

Figure 3 is a detached view of a brace back pad provided on its inner surface with a large number of transverse rubber strands 80 stitched closely adjacent to one another inside a border line which follows the outline of the pad.

Figures 4 and 4^a are detached views of a 85 modification of the brace back pad shown in Figure 3 showing in elevation and edge view respectively its inner surface covered with a sheet or layer of an adhesive material such as transversely corrugated rubber.

Figures 5 and 5^a are views similar to Figures 4 and 4^a showing the inner surface of the brace back pad covered with a sheet or layer of a granulous material such as crepe rubber having adhesive properties.

Figures 6, 7 and 8 are other views of different embodiments of a brace back pad as shown in Figures 1 and 2, the adhesive tapes or cords of chain-like structure fitting the inner surface of said pad being arranged obliquely according to different patterns.

Figure 9 is a fragmentary view showing a brace back strap the inner surface of which is fitted with vertically extending friction tapes or cords of chain-like structure.

5 Figure 10 is a fragmentary view similar to Figure 9 showing the invention as applied to braces of a slightly different construction, the inner surface of the back strap being fitted with a large number of rubber strands 10 closely stitched thereto.

10 Figure 11 is a view similar to Figure 9 showing a brace back strap and a back pad the inner surface of which is fitted with friction tapes or cords of chain-like structure 15 provided on either sides with quincuncial borders, the cords on the pad extending at right angles to the cords on the strap.

15 Figure 12 is a diagrammatic view showing the method of weaving the cords used in the embodiment shown in Figure 11.

20 Like reference characters designate like parts throughout the several views.

Reference being first had to Figures 1 and 2, it will be seen that the shoulder straps 2, 2 25 of the braces are connected with the back pad 1 by means of a double line of stitches 4 in Figure 1 and by means of a single line of stitches 5 in Figure 2.

25 The embodiments as represented in Figures 3 to 8 inclusive are similar to the one shown in Figure 1 but could be made of course similar to the one shown in Figure 2.

30 In any of the said embodiments, the inner surface of the brace back pad 1 is so formed as to normally exert a frictional or adhesive 35 effect on the underlying shirt or similar garment with a view to preventing the latter from puckering or wrinkling up under the wearer's stresses or motions.

40 The effect of friction or adhesion may be obtained of course in miscellaneous ways of which only a limited number are shown by way of examples.

45 According to Figures 1 and 2, the inner surface of the brace back pad 1 is fitted with a plurality of transversely extending and spaced cord-like protuberances 7 each formed of four parallel rubber strands stitched at short intervals to a fabric or other foundation which may conveniently form a lining for said pad or be the pad itself, the stitches being staggered from one strand to the next ones so as to give each protuberance 7 a chain-like structure which enhances the frictional effect.

50 According to Figure 3, the inner surface of the brace back pad 1 is lined with a frictional member formed of a fabric on which are stitched a large number of quincuncially 55 stitched rubber strands 9, the stitches being all confined within a border line 8 following the outline of the pad, said border line being for example a seam connecting the said fabric to the pad.

55 According to Figure 4, the inner surface of

the brace back pad 1 is lined with a sheet or layer of rubber 10 having transverse corrugations 10^a which impart the necessary adhesive power thereto, said rubber sheet or layer being for example cemented as shown 70 at 11 to the pad 1.

According to Figure 5, the inner surface of the brace pad 1 is lined with a sheet or layer of granulous or gripping material 12 such as crepe rubber having adhesive qualities, this adhesive sheet or layer being cemented as shown at 13 to the pad 1.

According to Figures 6, 7 and 8, the inner surface of the brace back pad 1 is fitted with a plurality of transversely extending and 80 spaced cord-like protuberances 7 of chain-like structure formed as described with reference to Figures 1 and 2, said protuberances 7 being arranged in V shape or inverted V shape as in Figures 6 and 7 or merely obliquely as in Figure 8.

According to Figure 9, the inner surface of the brace back strap 3 which extends downwardly from the brace back pad 1 to another pad 15 carrying tabs P formed with the usual button-holes (not shown) is provided with a plurality of substantially parallel and vertically extending cord-like protuberances 7 each formed of three rubber strands stitched to the strap 3 or to a piece of fabric covering 90 said strap at short intervals, the stitches being staggered from one strand to the next one to provide a chain-like structure which enhances the frictional effect.

According to Figure 10, the inner surface of the brace back strap 3 which extends down from the back pad 1 to a metal buckle B carrying an arch-shaped member A fitted at its ends with the usual buttonholes (not shown) is provided with a large number of closely arranged rubber strands 9 stitched transversely to the strap 3 or to a piece of fabric covering said strap.

According to Figure 11, the inner surface of the brace back strap 3 and back pad 1 is fitted with cord-like protuberances 7 each formed of four rubber strands stitched in staggered relation to one another and of quincuncially woven borders 7^a, the cord-like protuberances on the pad 1 extending at right angles to those on the strap 3.

By the provision of the borders 7^a advantageously made of textile material and so sized as to allow the rubber strands 7 to project out for contacting with the garment and checking its wrinkling tendency, the cord-like protuberances which functionally are exposed to wear due to friction are given a much longer life, while proper selection of the substances of which said borders are made permits them to better sustain the rubber strands and if required to aesthetically match with the other parts of the braces. Thus for example the textile threads of which the borders 7^a are made may be so chosen as to con-

trast in color with the rubber strands of the cords 7 and the fabric composing the braces.

An important function played by the quincuncially stitched borders 7^a is that they protect the sides of the rubber strands of the cords 7 from any tendency to shearing due to repeated frictions occurring between them and the garment.

A method of weaving cord-like protuberances 7 provided with borders 7^a as illustrated in Figure 11 is represented diagrammatically in Figure 12 wherein *a* designates the weft threads, *b* the rubber strands, *c* the textile threads forming the borders 7^a, *d*, *d* the textile warp threads forming the fabric foundation which may for example line the back strap 3 of the braces. As will be seen, the weave of the threads *d*, *d* is the ordinary or simple one used for cloth making.

It will be appreciated that the size and number of the cord-like protuberances 7 may vary to suit requirements. The size of the rubber strands may also vary depending upon the extent to which said protuberances must protrude to ensure proper friction and gripping against the shirt or other garment which it is desired to hold from puckering up.

It will also be appreciated that the cord-like protuberances 7 may be arranged according to any pattern so as, aesthetically speaking, to enhance the smartness of the braces.

Numerous details might be changed without departing from the scope of the subjoined claims.

What I claim and desire to secure by Letters Patent is:

1. A garment suspender including shoulder and back straps, and back pad interconnecting the same, said back pad having means projecting from the surface of the same for frictionally engaging a contiguous garment to prevent creeping and wrinkling of the latter incident to movements of the wearer.

2. A garment suspender including shoulder and back straps, and a back pad interconnecting the same, the back strap having means projecting from the surface of the same for frictionally engaging a contiguous garment to prevent creeping and wrinkling of the latter incident to movements of the wearer.

3. A garment suspender including shoulder and back straps, and a back pad interconnecting the same, certain of said aforementioned elements having a plurality of rows of stitches therein of material having a high coefficient of friction, the stitches in each row projecting from the surface of the element and being in longitudinally spaced relation to each other and in staggered relation with respect to the stitches of the adjacent row, for frictionally engaging a contiguous garment.

4. A garment suspender including shoulder and back straps, and a back pad interconnecting the same, certain of said aforementioned

elements having a plurality of parallel rows of stitches therein of strand rubber, the stitches in each row projecting from the surface of the element and being in longitudinally spaced relation to each other and in staggered relation with respect to the stitches of the adjacent row for frictionally engaging a contiguous garment.

5. A garment suspender including shoulder and back straps, and a back pad interconnecting the same, certain of said aforementioned elements having a plurality of parallel rows of stitches therein of strand rubber, the stitches in each row projecting from the surface of the element and being in longitudinal- 70

ly spaced relation to each other and in staggered relation with respect to the stitches of the adjacent row for frictionally engaging a contiguous garment, and a pair of quincuncially interrupted projecting borders formed of textile threads, said borders being of less height than the said rubber stitches.

6. A garment suspender including shoulder and back straps, and a back pad interconnecting the same, said back strap and back pad being provided with a plurality of protuberances having a high coefficient of friction, said protuberances being arranged in straight parallel rows on the back strap and in sets of parallel rows on the back pad, the rows of each set on the back pad being disposed at an angle with respect to the rows of the other sets, the protuberances of each row being in staggered relation with respect to the protuberances of the adjacent rows, and a pair of quincuncially interrupted projecting borders formed of textile threads of less height than the said protuberances.

In testimony whereof I affix my signature.

ALFRED LAURAIN. 105
